CLAIM

The ornamental design for a tray holder with drawer extended, as shown and described.

DESCRIPTION

FIG. 1 is a front top right-side perspective view of the tray holder with drawer extended of the present invention;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a bottom back left perspective view thereof.

The long dash, short dash broken lines in FIGS. 1 and 6 depict boundary lines and the areas within form no part of the claimed design. The remaining short dash, short dash broken lines depict portions of the article that form no part of the claimed design. None of the broken lines form part of the claimed design.
